UNITED STATES PATENT OFFICE

169,787

TELEVISION CABINET OR SIMILAR ARTICLE

Randall Rasmussen, Orem, Utah, assignor of one-sixth to Willard J. Hirst, one-sixth to Neils L. Rasmussen, both of Orem, one-sixth to Louis M. Wolsey, one-sixth to Sheldon F. Hirst, both of Provo, and one-sixth to Rex J. Wolsey, Springville, Utah

Application February 4, 1952, Serial No. 18,358

Term of patent 14 years

(Cl. D33—1)

To all whom it may concern:

Be it known that, I, Randall Rasmussen, a citizen of the United States, residing at Orem, in the county of Utah and State of Utah, have invented a new, original, and ornamental Design for a Television Cabinet or Similar Article, of which the following is a specification, reference being had to the accompanying drawing, forming part thereof.

The single drawing figure is a perspective view of a television cabinet or similar article, showing my new design.

I claim:

The ornamental design for a television cabinet or similar article, as shown.

RANDALL RASMUSSEN.
